(57) **CLAIM**

The ornamental design for a round luminaire, as shown and described.

DESCRIPTION

FIG. 1 is a bottom perspective view of a round luminaire showing a first embodiment of the new design;

FIG. 2 is a bottom plan view thereof;

FIG. 3 is a side elevation view thereof;

FIG. 4 is a top plan view thereof;

FIG. 5 is top perspective view thereof;

FIG. 6 is a bottom perspective view of a round luminaire showing a second embodiment of the new design;

FIG. 7 is a bottom plan view thereof;

FIG. 8 is a side elevation view thereof;

FIG. 9 is a top plan view thereof; and,

FIG. 10 is top perspective view thereof.

The broken-line disclosure in the views is understood to represent portions of the article in which the claimed design is embodied, but which form no part of the claimed design.
